SHEET-METAL RECEPTOR

Frank H. Richterkessing, Louisville, Ky., assignor
to Porcelain Metals Corporation of Kentucky,
Louisville, Ky.

Continuation of application Serial No. 518,480,
January 14, 1944. This application January 13,
1945, Serial No. 572,656

6 Claims. (Cl. 4—146)

1

The present application is a continuation of application Serial Number 518,480, filed by Frank H. Richterkessing and Benjamin F. Birdwell on January 14, 1944, and entitled Sheet-metal receptor.

My invention relates to improvements in "safety" or "non-slip" floors for bathing appliances and has particular reference to floors for shower-bath cabinets.

The primary object of this invention is to provide a floor for bathing appliances having a plurality of depressions or channels therein, which depressions extend substantially from the edges of the appliance to the drain therefor, to provide free drainage of water from substantially all portions of the floor and to provide anti-skid means for the floor.

A further object of this invention is to provide a floor having a plurality of depressions or channels therein, wherein the bottom portion of each channel is depressed substantially below the surface of the floor at a point remote from the drain and arranged so that the plane of the bottom portion of each channel merges substantially into the plane of the floor at a point adjacent the drain.

Another object of this invention is to provide a "safety floor" especially suitable for sheet-metal receptors used with bathing appliances known as shower-bath cabinets.

Another object of this invention is to provide a plurality of depressions in the floor of a sheet-metal receptor, which depressions generally reinforce the floor and permit the use of relatively thin sheet-metal that will not have a noticeable deflection or resiliency under the weight of a person on the floor.

A further object of this invention is to provide a floor in which the depressions are arranged to provide a distinct pattern, wherein the depressed areas are preferably coated with glazed vitreous enamel and the remaining areas of the floor preferably coated with an unglazed vitreous enamel.

A further object of this invention is to provide depressions or channels in a floor which taper in width from a relatively wide-channel remote from the drain to a relatively narrow-channel adjacent the drain so as to provide a "wedge-action" or "anti-skid" against slippage.

A further object of this invention is to place the drain substantially central of the receptor with the depressions extending substantially radially-outwardly from the drain.

Another object of this invention is to provide a floor for a bathing appliance having an anti-skid

2

design or pattern in the floor in which the pattern consists solely of depressions sloping toward and merging into the plane of the sloping floor at a point substantially adjacent the drain so as to eliminate "non-drainage" spots often encountered in constructions wherein the anti-skid arrangements consist of areas "raised" relative to the normal plane of the floor.

The advantages of these and other objects will become more apparent as the following description is read in connection with the accompanying drawings in which:

Figure 1 is a plan view of a receptor for a shower-bath cabinet;

Figure 2 is a sectional view taken along lines 2—2 of Figure 1;

Figure 3 is a sectional view taken along lines 3—3, on a greatly enlarged scale of Figure 1; and

Figure 4 is a portion of the section taken along lines 2—2 of Figure 1, shown in an enlarged scale to clearly illustrate the construction and relation of the depressions 14 relative to the floor 10 and drain 11.

Shower-bath cabinets to which the present invention has particular application are rapidly gaining in popularity and the use of sheet-metal receptors having a vitreous-enamel coating has been widely accepted as a very practical and economical construction for a shower-cabinet.

However, three problems have been encountered in the design of such equipment; (1) the slipperiness of vitreous-enamel surfaces; (2) the tendency of sheet-metal receptors to deflect or feel resilient under the weight of a person; and (3) the free drainage of water to the drain so as to eliminate accumulation of scum and soap stains on the surface which impair the appearance of the receptor and give the general impression of uncleanliness.

Unglazed vitreous enamel has been successfully used to impart non-slip qualities to vitreous-enamelled receptors and, by employing a special arrangement of unglazed vitreous enamel relative to glazed enamel, the free-drainage of water has been provided for to some extent.

The United States Letters Patent Numbers 2,292,368 and 2,292,369, issued to Charles T. Gordon August 11, 1942, and entitled, respectively, "Vitreous enamel bath floor" and "Method of producing anti-slip surfaces for bath floors," illustrate such uses of unglazed and glazed vitreous-enamel.

However, it is to be noted that these patents provide a vitreous-enamel surface having unglazed portions "elevated" relative to the remain-

ing glazed portions of the floor surface. While this arrangement constitutes a marked advance in receptor design, no provision is made for eliminating the deflection and resilient feel of the sheet-metal receptor under the weight of a person.

The present invention provides a construction that eliminates this objectionable deflection and resilient feel of the receptor under the weight of a person, and further utilizes the construction to provide anti-skid properties and drainage that is free from the non-drainage spots often encountered in constructions having the anti-skid areas "raised" relative to the normal plane of the floor.

In the following description the expression "unglazed vitreous enamel" has reference to enamel surfaces having a dull, matte, or granular surface of the type referred to and described in the aforesaid patents issued to Charles T. Gordon. However, it is to be understood that other non-slip vitreous-enamel surfaces may be employed and other substitutes made without departing from the spirit of this invention.

In the drawing, the numeral 10 designates the floor of the receptor, which receptor has a perimetrical flange 12 projecting vertically therefrom. As illustrated in Figure 2, the floor 10 slopes generally downwardly toward a central aperture 11 that provides a suitable drain outlet for waste laden water.

In Figure 1, the numeral 14 designates depressions or channels formed in the floor of the receptor, which depressions preferably have their surfaces coated with glazed, vitreous-enamel 14A. The numeral 13 designates the normal or flat portion of the floor of the receptor, which portion preferably has its surface coated with unglazed vitreous-enamel 13A.

As shown in Figures 2 and 3 the channels 14 are depressed below the surface 13 of the floor 10. Further, as illustrated in Figure 2, the channels 14 slope toward the aperture 11 and merge into the plane of the sloping floor substantially adjacent the aperture 11. Therefore, the ends of each channel remote from the aperture 11 are depressed below the flat surface 13, while the ends of each channel adjacent the aperture 11 merge into the plane of the sloping floor. Likewise, as shown in Figure 1, the channels are relatively wide at the ends farthest from the aperture 11, while the ends adjacent the aperture 11 are relatively narrow. This construction of the channels 14 provides a "wedge action" or anti-skid against slippage.

Thus, it will be apparent that the tapered channels 14 provide improved anti-skid properties, reinforce the sheet-metal floor, and provide channels for quickly and freely draining the waste water to the drain. Obviously, since the channels 14 are depressed below the surface of the floor 10, non-drainage spots are eliminated entirely.

Also, as shown in Figure 1, the invention refers generally to the arrangement of the channels 14 radially relative to the aperture 11, thus providing symmetrical conditions for the floor. Obviously, merging the bottom of each channel 14 into the plane of the floor substantially adjacent the drain, eliminates non-drainage spots at the discharge end of the channels and permits the waste water to discharge freely into drain.

While Figure 1 illustrates the channels as being rounded at their remote ends with straight sides tapering toward the drain, it is to be understood that the specific shape of the channels can be

changed without departing from the spirit of this invention, so long as the channels remain depressed relative to the plane of the floor; merge into the plane of the floor adjacent the drain; and become relatively narrow at their discharge end to provide the aforesaid "wedge-action."

Likewise, it is to be understood that although the invention is shown and described in its specific application to a sheet-metal receptor, certain of the features and constructions can be applied generally to the floor of any bathing appliance, and can be embodied in floors made from materials other than sheet-metal. Therefore, it is to be further understood that the invention is not to be limited other than by the scope of the appended claims.

Having thus described the invention, I claim:

1. A sheet-metal floor for a shower-bath cabinet having a plurality of depressions formed therein, and a vitreous-enamel coating on the upper surface of the said floor; the outer surface of the vitreous-enamel coating on the upper surface of the depressions having a smooth glazed-finish and the outer surface of the vitreous-enamel coating on the remaining portion of the floor having a finish dull and rough relative to the said glazed finish.

2. A floor for a bathing appliance having a drain opening, the said floor sloping downwardly towards the drain and having a plurality of channels therein extending generally in direction of the slope, each channel tapering longitudinally and having its narrow end substantially adjacent the drain with the bottom surface thereof sloping downwardly from a greater depth, in terms of the floor, adjacent the perimeter to a lesser depth adjacent the drain where said narrow end merges into the plane of said floor.

3. A floor for a bathing appliance having a drain opening, the said floor sloping downwardly towards the drain and having a plurality of channels therein extending generally in direction of the slope, each channel tapering in depth longitudinally and having its shallow end substantially adjacent the drain with the bottom surface thereof sloping from a greater depth, in terms of the floor, adjacent the perimeter to said shallow end where the latter merges into the plane of said floor adjacent the drain.

4. A floor for a shower bath cabinet having a drain opening therein and formed to slope downwardly from adjacent its perimetrical edge to the drain opening, the sloping portion of the floor having a plurality of shallow, relatively wide and elongated channels depressed below the surface of said sloping portion and arranged radially of said drain opening, the bottoms of said channels being flat throughout their length and having all portions thereof sloping towards said drain opening, wherein said channels decrease in depth from their outer ends towards the drain opening and merge into the plane of the floor adjacent the drain opening.

5. A floor for a shower bath cabinet having a drain opening therein and formed to slope downwardly from adjacent its perimetrical edge to the drain opening, the sloping portion of the floor having a plurality of shallow, relatively wide and elongated drainage channels depressed below the surface of said sloping portion and arranged radially of said drain opening, said channels being tapered in width substantially throughout their length with the narrow ends thereof located adjacent said drain opening, and the bottoms of said channels being flat throughout their length and

having all portions thereof sloping towards said drain opening.

6. A floor for a shower bath cabinet comprising a substantially square sheet metal plate of uniform thickness throughout and having a drain opening centrally thereof, said plate formed to provide four quadrant panel portions each sloping downwardly from adjacent its outer edge to the said drain opening, and each sloping panel portion of said plate having a plurality of shallow, relatively wide and elongated drainage channels depressed below the surface of said sloping panel portion and arranged radially of said drain opening, said channels being tapered in width substantially throughout their length with the narrow 15 ends thereof located adjacent said drain opening,

and the bottoms of said channels being flat throughout their length and having all portions thereof sloping towards said drain opening.
